UNITED STATES PATENT OFFICE.

LOUIS BLUMENTHAL, OF NEW YORK, N. Y.

EXTENSION WARDROBE-BED.

SPECIFICATION forming part of Letters Patent No. 498,614, dated May 30, 1893.

Application filed January 26, 1893. Serial No. 459,894. (No model.)

To all whom it may concern:

Be it known that I, LOUIS BLUMENTHAL, a citizen of the United States, residing at New York, in the county and State of New York, have invented new and useful Improvements 5 in Extension-Beds, of which the following is a specification.

This invention relates to an improvement in that class of beds known as extension or 10 folding beds and the invention consists in certain novel features pointed out in the following specification and claims and illustrated in the annexed drawings in which—

Figure 1, is a face view of the bed closed or 15 folded. Fig. 2, is a section along $x x$ Fig. 1. Fig. 3, is a section similar to Fig. 2 the bed being opened. Fig. 4, is a section along $y y$ Fig. 3. Fig. 5, is a detail view showing an inclined guide way.

20 In the drawings the letter A indicates a stationary casing or base, to which is jointed at B, the main bed frame C, in such manner as to provide a projecting part at the head end of the frame C, which is provided with an eye or loop E for engaging a hook or catch F pivoted to the front wall of the stationary casing and projecting inside the latter. The main bed frame C carries the sliding frame or extension D. The hook or catch F is provided 25 with an extension projecting in front of the stationary casing and constituting a foot piece G, so that the foot can be placed thereupon to release the hook or catch F from the eye or loop E, and thus permit the frame C to swing 30 down to the position indicated in Fig. 3.

The frame C has a main mattress or bed portion H jointed by loops or connections I to the frame C. The lower end of the main mattress H is held in position by a support K jointed 35 at L to the extension D. The support K is connected to the foot or feet N of the extension D by a link or connection M jointed to the support K and to the foot N. When the foot N is swung up or folded the support K is swung in the direction of arrow 1 (Fig. 3) 40 so as to raise the lower end of mattress portion H above the top of the extension mattress portion O leaving the extension D with its mattress portion O free to be pushed or 45 run into the main frame C.

The frame D has tongues or projections P running in the inclined grooves or guide ways

Q in the frame C. The tongues P are secured each by a screw or fastening R to a side of frame D and as the grooves Q do not run completely to the end of frame C (Fig. 5) the tongues P prevent the extension D being drawn entirely out of frame C unless the screws R are removed. The ways Q being inclined downward toward the head of the bed 55 the extension D as it is run into the frame C gradually sinks so that when the extension D is entirely in (Fig. 2) the mattress portion H will not have its top project above frame C.

The mattress portion H may have a further 60 support on frame C at S and said frame C may have folding legs T. The head rest U swings on the frame C at V and said rest has swinging legs W adapted to rest against a shoulder X on the main frame to keep the head rest in 65 position as seen in Fig. 3.

What I claim as new, and desire to secure by Letters Patent, is—

1. The combination with a stationary casing A, and a main bed frame C pivoted to the casing and provided with inclined ways, of a mattress H hinged at its head to the head portion of the main bed frame, a sliding bed frame or extension D engaging the inclined ways of the main bed frame, and a movable support 75 K carried by the sliding bed frame or extension and arranged to lift the foot end of the mattress to permit the sliding frame or extension to move thereunder, substantially as 80 described.

2. The combination with a stationary casing A, of a main bed section C provided with inclined ways and hinged to the casing to swing from a perpendicular to a horizontal position, a mattress hinged at its head to the main bed frame, and a sliding bed frame or extension D engaging the inclined ways and provided with a hinged support K at its inner end for lifting the foot end of the mattress, substantially as described.

3. The combination with a main bed frame having a mattress portion H, of a sliding bed frame or extension, and inclined ways on which said extension is made to travel, said extension being provided with a swinging support K, and having swinging legs to which said support is connected, so that when the legs are swung in or folded the support is actuated to raise the main mattress or bed por-

tion H to allow the extension to pass thereunder, substantially as described.

4. The combination with a main bed frame having a mattress portion H, of a sliding bed frame or extension, and inclined ways on which said extension is made to travel, said extension being provided with a swinging support K, and having swinging legs and a link M jointed to said legs and to the support, so that when the legs are swung in or folded the support is actuated to raise the main mattress or bed portion H to allow the extension to pass thereunder, substantially as described.

5. The combination with a main bed frame having a mattress portion, of a sliding bed frame or extension, and inclined ways on which said extension is made to travel, said extension being provided with a swinging support K for the foot of the main bed or mattress portion, and said main mattress portion

being hinged at its head to the main frame, substantially as described.

6. The combination with a main bed frame having a mattress portion, of a sliding bed frame or extension, and inclined ways on which said extension is made to travel, said extension being provided with a swinging support K for the main mattress portion, and a head rest made to swing on the main frame and provided with legs or supports, said main frame having a shoulder for supporting said legs to keep the head rest in position, substantially as described.

In testimony whereof I have hereunto set my hand in the presence of two subscribing witnesses.

LOUIS BLUMENTHAL.
